(57) **CLAIM**

The ornamental design for a camera, as shown and described.

DESCRIPTION

FIG. 1 is a front, top, right perspective view of a camera; FIG. 2 is a front, bottom, left perspective view thereof; FIG. 3 is a front view thereof; FIG. 4 is a back view thereof; FIG. 5 is a side view thereof; FIG. 6 is a side view thereof; FIG. 7 is a top view thereof; and, FIG. 8 is a bottom view thereof.

The broken lines in the drawings are shown for the purpose of illustrating portions of the camera and form no part of the claimed design.

Any combination of the illustrated features, including claimed features and non-claimed features, may be claimed in this application or a continuing application claiming priority to this application by converting any portion of the broken lines to solid lines, any portion of the solid lines to broken lines, or both.

1 Claim, 8 Drawing Sheets
